ELECTRON DISCHARGE DEVICE

Bernard Salzberg, East Orange, N. J., assignor,
by mesne assignments, to Radio Corporation
of America, a corporation of Delaware

Original application September 22, 1933, Serial
No. 690,504. Divided and this application Oc-
tober 4, 1935, Serial No. 43,465

3 Claims. (Cl. 250—27.5)

My invention relates to improvements in electron discharge devices, and its principal object is to provide an improved electron discharge device, particularly of the type having three or more electrodes and useful as an amplifier, which has more desirable characteristics and particularly a more nearly constant amplification factor than such tubes constructed in the usual way.

The present application is a division of my co-pending application Serial Number 690,504, filed September 22, 1933 and assigned to the same assignee as the present application.

The novel features which I believe to be characteristic of my invention are set forth with particularity in the appended claims, but the invention itself will best be understood by reference to the following description taken in connection with the accompanying drawing in which:

Figure 1 is a longitudinal section of an electron discharge device embodying my invention;

Figure 2 is a horizontal cross section of the electron discharge device shown in Figure 1 taken along the line 2—2 of Figure 1;

Figure 3 is a horizontal cross section of a modified form of the electron discharge device shown in Figure 1;

Figure 4 is a horizontal cross section of another modified form of the electron discharge device of Figure 1;

Figures 5 and 6 are diagrams for graphically comparing certain characteristics of an electron discharge device embodying my invention and of an electron discharge device of the conventional type.

Referring to the drawing, the electron discharge device shown in Figure 1 has a dome shaped evacuated envelope 9 with the usual re-entrant stem and press 10 and the usual base 11. The envelope or bulb 9 encloses a unipotential

cylindrical cathode 12 having a heater 13, a tubular helical grid electrode 14 supported from the press 10 on grid side rods 15 and 16; and a tubular anode or plate electrode 17, with side flanges 18 to which the plate support rods 19 are attached, the grid and anode being coaxial with and surrounding the cathode. The anode carries from the flanges 18 the upper mica spacer 20 by the metal straps 21 and the lower mica spacer 22 by similar metal straps 23.

In the tube shown in Figure 1 the helical grid 14 is, as best shown in Figure 2, elliptical in cross section, the anode 17 being of the conventional type and circular in cross section; in the modification shown in Figure 3 the grid 24 is made like the helical grid 14, but is circular in cross section,

the plate 25 being of elliptical cross section; and in the modification shown in Figure 4 the grid 26 and the anode 27 are both elliptical in cross section, and are set with their major axes perpendicular to each other. In these embodiments of my invention the spacing between the grid and anode is at a minimum at the grid side rods, and each construction illustrated produces a tube having improved characteristics, particularly an amplification factor which is substantially constant over a wide range of grid bias voltages.

The preferred explanation of the improved results observed in tubes embodying my invention can best be followed in connection with Figures 5 and 6, which are a graphical comparison of an electron discharge device made in accordance with my invention with an elliptical grid and a circular plate, and indicated by diagram A, with the usual electron discharge device with a circular grid and a circular plate and indicated by diagram B. Both diagrams represent a cross section of a tube having a straight cylindrical cathode 12, a tubular plate 17 circular in cross section and coaxial with the cathode, and helical grids of wire wound on two grid side rods 15 and 16. The grid 14 in diagram A is elliptical in cross section in accordance with my invention, and the grid 24 in diagram B is circular in cross section, as in the usual three electrode amplifier.

The flow of the electron stream from the cathode to the plate is hindered to some extent by the grid side rod and the electrostatic field around it, hence that part of the plate behind or in the electron shadow of the grid side rod receives less current than the other parts. In Figures 5 and 6 the dotted line circles concentric with the side rods 15 and marked "low voltage" represent the effective fields around the side rods when a low negative voltage is impressed on the grid. That part of the plate behind the grid side rod is in the "electron shadow" of this field, which hinders the flow of electrons from the cathode, and in effect reduces the effective emitting surface of the cathode. The extent of this "shadow" is represented in the diagrams by the portion of the anode 17 which lies between the dotted lines extending from the cathode to the plate and tangent to the circles representing the effective fields around the grid side rods. If the grid bias is increased so that its effective field is increased, as represented by the dotted line circles concentric with the side rods 16, the "shadow" on the plate is materially increased, as graphically shown by the dotted lines tangent to these dotted line circles. As the grid bias or

impressed negative voltage is increased the "shadow effect" is materially increased and the effective emitting surface of the cathode reduced.

The "shadow effect" causes the amplification factor or μ of the tube to be different for different impressed grid voltages. In the usual tube having a circular grid and plate, the μ for the various sectors of the grid is different, being greatest at the side rods, as the large side rods have a greater controlling effect on the electron stream than the small grid wire. The effective amplification factor of the tube is an average of the factors for the various sectors. As the grid is made more negative the "shadow effect" is increased and the effective surface of the cathode reduced until at some negative bias the emission from those parts of the cathode adjacent the grid rods cannot reach the plate and is practically cut off. Whereupon those portions of the grid causing this cut-off are no longer effective in controlling variations in the electron flow to the plate. The portions of the grid which first reach the cut-off stage are the side rods and the parts nearest the side rods, and since the μ is the greatest at these portions of the grid, the effective amplification factor of the grid is made to depend on the lower μ sections and the effective amplification of the tube is therefore decreased. The higher the impressed negative voltage, the greater the "shadow effect" and the lower the effective amplification factor of the tube. This characteristic is particularly objectionable in an amplifier, such as an audio amplifier designed for constant μ tubes, since the amplifier is depended upon to reproduce faithfully in its output circuit the variations in voltage applied to the grid of the tube in the input circuit. If the more negative impressed grid voltages are amplified to a lesser extent than the less negative impressed grid voltages, as is done in the conventional tube, distortion in the output circuit of the tube will result, hence the grid swings in the usual tube having a circular anode and grid, must be limited to a narrow range to avoid this distortion.

My invention reduces this undesirable shadow effect to a minimum and makes the amplification factor more nearly constant, as appears from Figure 5 which shows that with the elliptical grid and circular plate the "shadow effect" caused by the effective field around the grid side rods is not only materially less for both low and high bias than with a circular grid and circular plate, but also that the "shadow effect" does not change as much with changes in the bias of the grid. In a tube embodying my invention the side rods 15 and 16 are spaced at the minimum distance from the plate 17, and do not exert as much retarding effect on the electrons leaving the cathode as the side rods of the usual circular grid. As those portions of my grid which correspond to the higher μ sectors of the conventional circular grid are closer to the plate than the sectors corresponding to the lower μ sectors, the various sectors have substantially the same μ , and also due to the resulting larger effective emitting area of the cathode, the mutual conductance of the tube is increased.

In accordance with my invention the plate may be circular in cross section and the grid elliptical, or the plate elliptical and the grid circular, or both elliptical with their major axis perpendicular, but in all cases the spacing between the plate and the grid electrode is a minimum at the grid side rods.

An elliptical type grid permits the greatest separation between the cathode and side rods for a given transconductance. Placing the grid side rods further away from the cathode decreases the chance of short circuits between the grid and the cathode, decreases grid emission, as the grid heating is less, and permits the distance between the grid rod holes in the mica spacers to be increased, whereby the spacers are stronger than in the usual type of construction.

My invention is of considerable utility in multi-grid tubes, such as space-charge grid tubes and similar tubes in which the grid nearest the cathode is at a positive potential with respect to the cathode. The side rods of such positive grids of the round type draw a high current which is out of proportion to the value as a control section of the grid. The side rods of an elliptical space-charge grid are much further away from the cathode, have less effect, and draw appreciably less current with the result that the amplification factor is more nearly constant.

In addition to the advantages of the elliptical grid structure for the grid nearest the cathode, it is found that this structure is also of advantage for other grids in the tube. It permits the side rods of the various grids to be separated sufficiently to meet the requirements of good mechanical design, and at the same time permits the wires of the different grids to be as close together as is desirable for electrical reasons for the best operation of the various grids.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having a straight cylindrical cathode, a tubular grid electrode surrounding and coaxial with said cathode and having side rods parallel to said cathode, a tubular plate electrode surrounding said grid electrode and coaxial with said cathode, said plate electrode being elliptical in cross section, the spacing between said electrodes being at a minimum at said side rods.

2. An electron discharge device having a straight cylindrical cathode, a tubular grid electrode surrounding and coaxial with said cathode and having side rods parallel to said cathode, a tubular electrode surrounding said grid electrode and co-axial with said cathode, said grid electrode being circular in cross section and said tubular electrode surrounding said grid electrode being elliptical in cross section, the spacing between said electrodes being at a minimum at said side rods.

3. An electron discharge device having a straight cathode circular in cross section, a tubular grid electrode surrounding and coaxial with said cathode and having side rods parallel to said cathode, a tubular plate electrode surrounding said grid electrode and coaxial with said cathode, said electrodes being elliptical in cross-section and mounted with their major axes perpendicular to each other, said grid side rods lying in a plane passing through the major axis of said grid.
